UNITED STATES PATENT OFFICE

JOHANN ZAGORSKI, OF FRANKFORT-ON-THE-MAIN, GERMANY

HIGH-TENSION CONDUCTOR

Application filed February 1, 1929, Serial No. 336,778, and in Germany May 6, 1927.

This invention relates to a high-tension conductor.

For conducting high-tension electric energy it is usual to employ conductors of large diameter, which may also be designed as hollow conductors. In order to prevent, as far as possible, losses of energy through radiation, the smoothest possible surface is given to both solid and hollow conductors by making the outer layer at least, of the conductor, of special strip sections. Owing to the large diameters employed and the low flexibility of the strip sections, such conductors are naturally far more rigid than the conductors generally employed for lower voltages and constructed of laid round wires.

It has hitherto been considered that high-tension conductors also ought to be made as flexible as possible; and in cases where the outside layer or sheath of the conductor was made in the usual way, by laying, attempts were made to attain this result by employing the largest possible number of strips for the covering layer. Thus for example, solid conductors with an external diameter of about 32 mm. (steel-aluminium conductors) had a covering layer of up to 48 wires, and hollow conductors of the type used in Germany, with an external diameter of 42 mm. had an outer layer of at least 24 wires.

It has transpired that these conductors are still subject to certain drawbacks liable to endanger their life considerably. In particular, torsional stresses are set up in these wires by the rope tension, in consequence of the twist produced in laying. These forces set up a considerable stressing of the conductor just in front of the places where it is gripped in the suspension and straining clamps, through permanent flexions and the like, which stressing could only be partially counteracted by correspondingly strengthening the design of the clamping members.

A similarly injurious effect is produced by the oscillations (set up by the wind and the like) always observable in the sections between the straining devices, and especially in overhead conductors of large cross section. In such cases the material which suffers most is that of the insulating chains, through the sudden

tensional stresses which inevitably result from said oscillation.

It has now been ascertained that when conductors are employed, which are made of strip sections, or with a covering layer of strip sections, the torsional stresses occurring in the overhead conductors when in position for use can be prevented, in a practically complete manner, and the injurious effects of the oscillations of the conductor prevented to some extent, by extremely simple measures; all that is necessary being merely to employ sufficiently wide strips in making the outside layer.

According to the present invention, the width of the flat wires of which the outermost layer, at least, of the conductor is composed, should be such that the ratio of the diameter D of the conductor, in millimetres, to the number Z of the wires in the outer layer should exceed 2, that is to say.

$$\frac{D}{Z} > 2.$$

It has been found of particular advantage for the ratio D to Z to be about 4. The high-tension conductors to which the present invention has reference are to be understood as those having a greater diameter than about 20 mm.

It has unexpectedly transpired that the greater rigidity of conductors constructed in accordance with the invention offers no substantial hindrance to their transport and erection. As before, the conductors can be coiled on suitable drums and the dreaded gaping between the individual sections of the outer layer can also be prevented, especially when their divergence in the radial direction is prevented by a suitable design for the strip sections of the outer layer, for example by providing them with tongue and groove joints.

Moreover, the greater rigidity of the conductors constructed in accordance with the invention has a powerful damping effect on the oscillation between the points of support. The small number of joints between the strips also naturally makes the surface of the conductors substantially smoother, so

that the electrical losses by radiation are low. A further advantage is that the cost of manufacture of the conductors is cheaper, owing to the greatly reduced number of the wire sections of which the conductors are composed.

In order more clearly to understand the invention, reference is made to the accompanying drawings in which:

10 Fig. 1 shows the cross section of a solid conductor with an external diameter of 25 mm., the covering layer, c , of which is built up, in accordance with the invention, of six strip sections.

15 Fig. 2 represents a hollow conductor, 32 mm. in diameter, and with eight strip sections d built up in the same manner.

20 Figs. 3 and 4 represent the moment of resistance of similar cross sections of strips in relation to their axis. From these figures it can be seen that the moment of resistance, referred to the axis $x-x$ in Fig. 3 is a multiple of that represented in Fig. 4, which is referred to the axis $y-y$.

25 In stretched laid conductors, the rope tension acts by tending to straighten out again the wires of the conductor which the operation of laying has disposed in approximately a spiral line of steep pitch.

30 Consequently, since the wires in the conductor are subjected to flexion by the rotational forces set up by the rope tension, such flexion corresponding to the moment of resistance of their cross section, referred to the 35 axis $x-x$, the invention enables the moment of resistance of the wires to be increased, by increasing the dimension a to such an extent that the torsional stresses are counteracted to a considerable degree or with practical 40 completeness.

The high-tension conductors under consideration are particularly those employed for working voltages of 150 kw. or higher, and having an external diameter of at least 45 20 mm. Under these working conditions, the hollow conductor of the invention has proved particularly advantageous.

I claim:

1: A hollow high tension conductor having 50 a diameter of more than 20 mm. comprising a plurality of spirally arranged interlocking strips equal in number to one-fourth to one-half of the number which indicates the diameter of the conductor in millimeters.

55 2. A hollow high tension conductor having a diameter more than 20 mm. comprising a plurality of spirally arranged strips provided with tongues and grooves at their contacting edges, equal in number to one-fourth to one-half of the number which indicates the diameter of the conductor in millimeters.

60 3. A flexible self-sustaining hollow conductor having a diameter of more than 20 mm. comprising a plurality of interlocked spiral longitudinally extending strips pro-

vided with tongues and grooves at their contacting edges, equal in number to one-fourth to one-half of the number which indicates the diameter of the conductor in millimeters.

In testimony whereof I affix my signature. 70
